SMOKING PIPE

Frank M. Lingo, Columbus, Ohio

Application June 21, 1938, Serial No. 214,946

1 Claim. (Cl. 131—222)

My invention relates to a smoking pipe. It has to do, more particularly, with a novel type of pipe for smoking tobacco.

Attempts have been made in the past to provide a suitable pipe having means for preventing the moisture from the mouth reaching the bowl of the pipe interfering with proper combustion of the tobacco, producing a deposit in the bottom of the bowl and also resulting in an unpleasant taste. Prior art pipes designed to overcome this disadvantage have consisted of a main bowl or body portion and a separate bowl or liner disposed therein. In some of these prior art pipes, the liner has been permanently secured in the main bowl. Obviously, it would be desirable to mount the liner in such a manner that it could be readily removed. In other prior art pipes, the liner has been removable. However, no satisfactory simple means has been provided for locking the liner in position. It is desirable that the locking means be extremely simple and inexpensive and be of such a nature that although it will efficiently lock the removable bowl or liner in position, the liner or bowl can be quickly and easily removed when desired.

One of the objects of my invention is to provide a smoking pipe which is so constructed that the moisture from the mouth of a person using the pipe will be prevented from reaching the chamber in which the tobacco is disposed and where combustion takes place.

Another object of my invention is to provide a pipe of the type indicated which embodies a main body portion or bowl having a removable bowl or liner disposed therein, and which is provided with simple and effective means for locking the liner in position but which can be readily operated to permit removal of the liner when desired.

The preferred embodiment of my invention is illustrated in the accompanying drawing wherein similar characters of reference designate corresponding parts and wherein:

Figure 1 is a longitudinal section taken through a pipe made in accordance with my invention.

Figure 2 is a perspective view, partly broken away, showing the removable liner or bowl removed from the body portion and showing the stem removed from its socket.

Figure 3 is a perspective view showing a liner or bowl of slightly different form.

Figure 4 is a vertical section taken through the composite bowl of the pipe substantially along line 4—4 of Figure 5 showing the liner illustrated in Figure 3 mounted therein.

Figure 5 is a plan view of the structure illustrated in Figure 4.

With reference to the drawing, in Figures 1 and 2 I have shown a pipe made in accordance with my invention. This pipe comprises a main body portion 1 which includes a bowl member 2 having a shank 3 projecting therefrom. This shank has a longitudinal passageway 4 extending therethrough and communicating at its inner end with the interior of the bowl 2 at the lower end thereof. The bowl 2 may be of annular cross section as shown having inwardly tapering or curved side walls 5 and a substantially flat bottom surface 6. However, the bowl may be of other shapes.

The bowl 2 is adapted to receive a separate removable liner or bowl 7 which has an outer surface corresponding in contour substantially to the contour of the inner surface of the bowl 2 so that it will fit snugly therein. The upper end of the member 7 is provided with an enlarged portion 8 so that a shoulder 9 is formed which will rest on the upper edge of the bowl 2. Adjacent its lower end and on the exterior thereof, the member 7 is provided with an annular groove 10 formed therein. When the member 7 is positioned in the bowl 2, the groove 10 will be at the same level as the passageway 4 and the inner end of the passageway 4 will communicate with the groove. A plurality of small outwardly and downwardly directed ducts 11 are provided for establishing communication between the interior of the removable bowl 7 and the groove 10. The extreme lower end of the member 7 is provided with a plurality of vertically disposed notches 12 which are spaced circumferentially around the member 7. These notches 12 extend from the groove 10 downwardly to the extreme lower end of the member 7.

A stem 13 is adapted to be associated with the body portion 1. This stem has a reduced tubular inner portion 14 which fits snugly into the passageway 4 formed in the shank 3. This stem has a passageway 15 extending therethrough. The inner end of the stem has a tongue 16 formed thereon which will project into the groove 10 when the removable bowl 7 is mounted in position in the bowl 2 and when the stem 13 is properly positioned on the body portion 1 with the shoulder 17 of the stem abutting the outer end of the shank 3. It will be noted from Figure 1 that since the tongue 16 projects into the groove 10, the bowl 7 will be securely locked in position in the bowl 2. Thus, when knocking the ashes from the pipe, there will be no danger of the

removable bowl 7 dropping from the bowl 2. To remove the bowl or liner 7 from the bowl 2, it is merely necessary to withdraw the portion 14 of the stem thereby withdrawing the tongue 16 from the groove 10.

5 In using this pipe, it will be apparent that the moisture from the mouth of the smoker will be prevented from reaching the interior of the removable bowl 7. Any moisture passing rearwardly through the stem 13 will pass into the groove 10 and will drop downwardly through the notches 12. Although the bowl 7 is entirely independent of the stem 13, a proper draft will be provided since the smoke will pass from the interior of the bowl 7 through the ducts 11, through groove 10 and will be drawn from the groove through the passageway 15 in the stem. If small particles of ash pass through ducts 11 into groove 10, such particles will drop downwardly through notches 12, some of which are in alignment with the ducts, and will not reach the stem.

10 In Figures 3, 4 and 5 I show a pipe of slightly different construction. In this form the body portion 1 and the stem are exactly the same as in the structure previously described. However, instead of having a groove 10 extending entirely around the removable bowl I provide a groove 10a which extends only substantially half-way around the member 7a. As indicated in Figure 4, at each end of this groove I provide a duct 11a 15 for establishing communication between the interior of the bowl 7a and the groove 10a. Directly below each of the ducts 11a is a vertically disposed notch 12a of V-shaped cross section 20 which extends from the groove 10a to the lower end of the member 7a. The tongue 16 of the stem will extend into the groove 10a and will serve to lock the member 7a in position. Any moisture entering the groove 10a will drop downwardly through the notches 12a. Furthermore, 25 if small particles of ash drop through the ducts

11a, they will drop down through the notches 12a and will not pass to the stem.

It will be apparent from the above description that I have provided a smoking pipe having many advantages. Since the removable bowl is separate from the stem, no moisture from the mouth of the smoker will reach the bowl. Although the bowl is readily removable, it is efficiently locked in position by the projecting tongue carried by the stem. However, the bowl may be readily removed when desired for cleaning purposes or it may be replaced by a new bowl when it becomes burnt too much or becomes too strong.

30 Various other objects and advantages will be apparent from the preceding description, the drawing and the following claim.

Having thus described my invention, what I claim is:

A smoking pipe comprising a main bowl member, a removable bowl member disposed in said main bowl member, said main bowl member having an opening leading thereinto, a stem adapted to be slipped into and out of said opening and normally having one end extending into said opening, said removable bowl member having a 20 horizontally disposed groove formed in the exterior surface thereof in alignment with said opening, said stem having a tongue formed on its inner end projecting into said groove and adapted to contact a portion of the wall surface 25 of the groove in order to lock said removable bowl member in position, and ducts extending through the wall of said removable bowl member and into said groove for providing communication between the interior of said removable 30 bowl member and said stem, said tongue being adapted to cooperate with any portion of the groove abutting the tongue to constitute a lock therewith.

FRANK M. LINGO.
